UNITED STATES PATENT OFFICE.

HENRY C. REW, OF CHICAGO, ILLINOIS.

APPARATUS FOR MANUFACTURING GAS.

SPECIFICATION forming part of Letters Patent No. 341,506, dated May 11, 1886.

Application filed November 14, 1885. Serial No. 182,875. (No model.)

To all whom it may concern:

Be it known that I, HENRY C. REW, of Chicago, in the county of Cook and State of Illinois, have invented certain new and useful Improvements in Apparatus for Manufacturing Gas; and I do hereby declare that the following is a full, clear, and exact description of the same, which will enable others skilled in the art to which it appertains to make and use the same, reference being had to the accompanying drawing, and to the letters of reference marked thereon, which form a part of this specification.

This invention relates to the manufacture of gas, and is an improvement on the cupola process and apparatus, as hereinafter described.

Heretofore in the manufacture of gas by the single cupola process, where the fuel or combustion chamber provided with a direct air-blast has been located in the upper part of the cupola and the fixing-chamber below, no provision has been made for the superheating of the steam before bringing it in contact with the carbonaceous material. Furthermore, but a single fire has been used for the decomposition of the steam. Experience has now abundantly demonstrated the fact that steam cannot be completely decomposed by passing it through a single fire, as but a very limited and insufficient quantity of white-hot fuel suitable for that purpose can be provided in a single cupola. The gas manufactured in a single cupola is therefore of poor quality. The steam being only partially decomposed, the gas does not become thoroughly fixed, and is left in a somewhat vaporous condition, which condenses and stops the burners with tar at a moderate distance from the works. Furthermore, grate-bars have been used, which are soon destroyed by the action of the hot gases, and the ash-pit has been so constructed that the ashes were driven into the fixing-chamber by the operation of the blast, thereby choking up and obstructing the passages and spaces in the loose brick-work.

The object of this improvement is, therefore, as follows: First, to thoroughly superheat the steam to its decomposing temperature before bringing it in contact with the carbonaceous material for decomposition; second, to provide a much larger and sufficient supply of

white-hot fuel for the complete and perfect decomposition of the steam; third, to dispense with grate-bars in a cupola generating-furnace having the fuel-chamber located above the superheating or fixing-chamber, and to so construct the combustion-chambers and the ash-pits that little or no ashes will be driven into the superheating and fixing chambers by the operation of the air-blast.

Having stated the nature and object of my invention, I will now proceed to describe it more particularly with reference to the accompanying drawing, which forms part of this specification.

The drawing represents a vertical section of my improved apparatus.

Two cupolas are used, having the combustion-chambers A A' located in the upper part 70 of each cupola, and the superheating-chamber B and the gas-fixing chamber B', loosely filled with brick-work, located below the combustion-chambers, as shown. Brick-work arches separate the fuel-chambers A A' from 75 chambers B B'. The cupolas are connected by the flue E in the upper part of the combustion-chamber, and flues D D', provided with valves d d', lead from flue E to the tops of chambers B B', for conducting products of combustion 80 from the tops of fuel-chambers A A' to the tops of the superheating and fixing chambers B B'. Flues F F', having valves f f', connect the bases of chambers A A' with the tops of chambers B B'. Air-blasts C C', having valves c c', 85 connect with annular flues P P', having tuyeres or ports p p' leading into the bases of the fuel-chambers A A'. Perforated brick arches for supporting the brick-work are located at the bases of chambers B B', forming chambers I I'. 90 Outlet-pipes G G', for products of combustion, controlled by safety-valves g g', extend from chambers I I', and pipe K, having valve k, for the outlet of gas, extends from pipe G'. Supply-pipes L, M, and N, (having controlling-valves,) respectively, for air, steam, and gas, connect with chamber I of superheating-chamber B. Steam and oil supply pipes J H' connect with the top of the fixing-chamber B'.

The operation of the apparatus is as follows: 100 The combustion-chambers A A' are suitably charged with carbonaceous material and ignited, and the valves d and d' in the flues D and D' and the valves g g' in the outlet-flues

G G' are opened. The fires are simultaneously urged by an air-blast admitted through the pipes C C', controlled by valves c c'. P and P' represent annular flues running entirely round each combustion-chamber, which are connected with the combustion-chambers by the tuyere-holes p p'. The air is driven through the annular flues and tuyere-holes and enters the fuel in the combustion-chambers from every side. The products of combustion and gases generated are driven upward through the fuel and then downward through the flues E and D D' into the upper part of the superheating and fixing chambers B and B'. Air from the annular flues is also admitted with the hot gases into those chambers through the flues F F', controlled by valves f f', which causes the gases to burn, and the hot products pass downward through the chambers B B', highly heating the loose brick-work therein contained. When properly heated, the air-blast is shut off and the valves d d' in the flues D D' are closed. Steam is then admitted at the top of chambers B B' through pipes H H', which drives out the products of combustion remaining in the brick-work. The valves g g' in the flues G G' are then closed, the gas-outlet valve k in the pipe K is opened, and the apparatus is then ready to manufacture and fix gas. Steam, air, or gas, or any mixture of the same, is then admitted at the bottom of the superheating-chamber B through pipes L, M, and N, and the mixed gases are driven up through the brick-work, where they are heated to their decomposing-temperature. From the upper part of chamber B the mixed gases pass up through flue F and through the annular flue P and tuyere-holes p into the combustion-chamber, where they are wholly or partially decomposed in contact with the incandescent carbonaceous material. The gases generated are then driven through the flue E into the adjoining combustion-chamber A', and down through the incandescent fuel, where the operation of thoroughly decomposing the mixed gases is completed. The gases then pass downward through the flue F' into the fixing-chamber B', and down through the heated refractory material, becoming thereby fixed into a homogeneous gas, then out through the pipe K to the main. A test-burner is connected with the pipe K, and in case the gas needs enriching oil or oil vapors may be injected in the upper part of the fixing-chamber B' through pipe J, which will be combined and fixed with the gases in their passage through the fixing-chamber, and a fixed gas of any desired candle-power can thus be manufactured. Air or a non-illuminating gas or steam can be used separately and driven into the bottom of chamber B through pipes L, M, or N, and thus utilized as a medium for the manufacture of gas, according to the material used in the combustion-chambers A A' and the quality of gases that it is desired to manufacture.

The combustion-chambers A A' are charged with fuel through the tight feeding apparatus

O O', in order that no heat and gas may be allowed to escape when fuel is charged in. The ashes are removed from the bottom of the combustion-chambers through the doors R R', located below the annular flues P P' and the tuyere-holes p p'.

The advantages gained by my improved apparatus are as follows: First, the steam is highly superheated to its decomposing-temperature before coming in contact with the carbonaceous material; second, the mixed gases previously heated to their decomposing-temperature are driven through two combustion-chambers and in contact with a much larger supply of incandescent carbonaceous material as compared with apparatus containing only one combustion-chamber, by which means they are thoroughly and completely decomposed, and a fixed gas of much higher quality and capable of being carried through pipes for any reasonable distance without condensing is manufactured; third, the operation of the air-blast is such that little or no ashes are blown from the combustion-chambers into the superheating and fixing chambers B B', by which means the passages through the loose brick-work are left more free and open for the passage of the gases, as described.

Having thus described the apparatus, what I claim as my invention, and desire to secure by Letters Patent, is as follows:

1. The combination of the combustion and generating chambers A A', having the connecting-flue E at the top thereof, the superheating and fixing chambers B B', located below chambers A A', the outlets for products of combustion D D', connecting the tops of chambers A A' with chambers B B'; and air-inlets C C', all connected as described.

2. The combination of the combustion-chamber A, the superheating-chamber B, the flues F E D, connected, as described, with the combustion-chamber A', and the gas-fixing chamber B', having the flues F' E D', as and for the purpose described.

3. The combination of the combustion-chamber A, the superheating-chamber B, the combustion-chamber A', and the gas-fixing chamber B', with the gas, steam, air, and oil inlets, and flue E, connecting, as described, and the outlets for products of combustion and gas connecting with the bases of chambers B B', for the purpose described.

4. The combination of the combustion-chamber A, the superheating-chamber B, having a steam-supply pipe and an outlet for products of combustion connecting at its base with the combustion-chamber A', the gas-fixing chamber B', having an oil-supply pipe, and the flue E, connecting-chambers A A' at the top, and outlet-pipes for products of combustion and gas leading from the base of chamber B', as shown and described.
